UNITED STATES PATENT OFFICE.

JOHN A. WEBER, OF TOLEDO, OHIO.

TRACK-SWITCH MECHANISM.

1,323,510.

Specification of Letters Patent.

Patented Dec. 2, 1919.

Application filed April 11, 1917. Serial No. 161,325.

To all whom it may concern:

Be it known that I, JOHN A. WEBER, a citizen of the United States, and a resident of Toledo, in the county of Lucas and State 5 of Ohio, have invented a certain new and useful Track-Switch Mechanism; and I do hereby declare the following to be a full, clear, and exact description of the invention, such as will enable others skilled in the 10 art to which it appertains to make and use the same, reference being had to the accompanying drawings, and to the characters of reference marked thereon, which form a part of this specification.

15 My invention relates to track switch mechanism, and it has for its object to provide a means carried in close proximity to the front wheel of the truck of the car for operating the track switch. It also has for 20 its object to provide a track switch engaging means which will readily enter the truck channel and will automatically turn so as to engage the nose of the track switch. It also has for its object to provide means for 25 operating the switches on either side of the track and to throw the switches in either direction.

The invention may be contained in many 30 forms of constructions usable for operating track switches, all of which come within the purview of my claims hereinafter appended. To show the practicability of my invention I have selected one of such constructions as an example and shall describe 35 it hereinafter. The construction selected is illustrated in the accompanying drawings.

Figure 1 of the drawings illustrates a side view of the track switch operating mechanism showing the part of the mechanism 40 which is used in connection with the left hand side of the track and also showing a section of parts connecting the parts which operate the switches on both sides of the track. Fig. 2 is a top view of the manual means for operating the switch throwing mechanism. Fig. 3 is a sectional view of the manual means illustrated in Fig. 2 taken on the line 3—3 indicated in Fig. 2. Fig. 4 is a front view of a foot operating mechanism 45 which coacts with the manual means illustrated in Fig. 2 for operating the track switch mechanism. Fig. 5 is a side view of the part illustrated in Fig. 4. Fig. 6 is a top view of the part illustrated in Figs. 4 and 5. Figs. 7, 8 and 9 illustrate machine 50 elements which are shown assembled in

Figs. 4, 5 and 6. Fig. 10 illustrates a top view of the switch operating mechanism. Fig. 11 illustrates a top view of a shifting means for throwing the track switch operating mechanism into position to throw the switch point to the right or to the left. Fig. 12 illustrates a sectional view of the part illustrated in Fig. 11 taken on the line 12—12 indicated in Fig. 11. Fig. 13 is an 60 end view of the part illustrated in Fig. 11. Fig. 14 illustrates a means for operating the part illustrated in Figs. 11, 12 and 13. 65

1 is the frame of the car which is illustrated in dotted lines in Fig. 1. 2 is the truck, and 3, 3 are wheels, which are also illustrated in dotted lines. 4 is the track having the switch 5. The mechanism is shown in position for throwing the switch of the left-hand track to the right to permit 70 the car to proceed on the main line instead of turning onto a branch. 75

The switches 5 are operated by disks 6 and 7, which are pivoted on the ends of arms 8 and 9. The disks 6 and 7 are located preferably in line with the flanges of the wheels 3 and thus are located directly above the channels of the tracks and in the planes of the flanges of the wheels. The arms 8 and 9 are pivoted to frames 10 and 11. The 80 frames 10 and 11 are pivotally supported on the axles of the wheels 3. The arms 8 and 9 are connected to channeled members 12 and 13 by links 14 and caps 20. Each link 14 connects one end of a channeled member to 85 one end of an arm. Each channeled member is provided with a slot 15 through which a rod 16 extends into the channeled member. The channeled members are preferably made 90 cylindrical and are provided with plugs 17 which close the ends of the members. When 95 made cylindrical the rods 16 are connected to balls 18 which loosely fit the interior of the members and may be slid along the members. The members are pivoted to the 100 frame 10 by means of the pin 19, so that when the ball 18 is shifted to one end of a member and the rod 16 connected to the ball is moved, it will cause movement of the arm 8 or 9 to which it may be connected by the 105 link 14 in one direction and cause the opposite movement of the arm when the rod 16 is moved in the same direction and the ball 18 is shifted to the opposite end of the member. By this means the disk 6 or 7 may be 110 shifted to angular position relative to the tracks by forward movements of the rods 16

and so as to throw the switches of either rail or either side of the track to the right or to the left, according to the position of the balls 18 within the members 12 and 13. This is 5 done after the disks 6 and 7 are lowered into the channels of the track.

The rods 16, which are connected to the balls 18 and operate to place the disks 6 and 7 in their different angular positions, extend 10 through fingers 21, forming parts of a bell crank lever 22, which are pivoted to the frames 10 and 11. A compression spring 23 is located intermediate the fingers 21 and collars 24. Limiting collars 25 are also 15 keyed or secured to the rod 16 to prevent the compression springs 23 from forcing the rods out of the fingers 21. The springs 23, when the bell crank levers 22 are turned forward, operate to yieldingly push the rod 16 20 forward and to hold the disks in their angular positions to which they are turned by the shifting of the rods 16 and the balls 18, also to cause the shifting of the disks from position in the planes of the flanges of the wheels 25 to either one of their angular positions relative to the rails when the rods 16 are shifted so that the balls 18 are located in the ends of the members 12 and 13. The bell crank levers 22 are also connected by springs 26 to 30 brackets 27 which are secured to the frame 1. The springs 26 yieldingly prevent rotation of the bell crank levers 22. They also yieldingly prevent and cause the return of 35 links and levers connected directly or indirectly to the bell crank levers 22. The levers 22 are provided with stops 58 to limit the movements of the levers 22.

The bell crank levers 22 are connected by 40 links 28 to bell crank levers 29 which are pivotally supported in brackets 27. The bell crank levers 29 are connected by rods 30 to bell crank levers 31 and 32 which are supported on shafts 33. The shafts 33 are supported in brackets 34 which are secured to 45 the frame 1 of the car. When one or the other of the bell crank levers 31 or 32 is rotated on the shaft 33 one or the other of the bell crank levers 29 is rotated, which pulls on the short arm of the bell crank lever 22 and causes one of the frames 10 or 11 to rotate 50 about the axle of the wheel on which the frame is supported, inasmuch as the spring 26 operating upon the long arm of the bell crank lever 22 resists rotation of the bell 55 crank lever 22 of the frame 10 or 11 to which it may be connected, and thus the frame 10 or 11 is yieldingly turned downward until the disk in which it is connected is placed in the channel of the track.

60 Either of the frames 10 or 11 may be rotated about the axle by means of a pedal rod 35, which is connected by slot and pin to a lever 36, which is also pivoted on the shaft 33. A spring 37 is connected to the 65 lever 36 and to the frame 1 of the car to

yieldingly resist the movement of the pedal and cause the return of the lever 36 against the cross rod 59. Arms 38 are also pivotally supported on the shaft 33 and may be slid along the shaft by means of the rod 39 having pins 40 which extend into channels 41. The arms 38 are provided at their outer ends with pins 42 which are secured in the arms 38 and extend into the bell crank levers 31 and 32. When the rod 39 75 is shifted, one of the pins 42 is pushed through either the bell crank lever 31 or the bell crank lever 32 and so as to extend a short distance to the opposite side of the bell crank lever 31 or 32. The bell crank 80 lever 36 is provided with a half boss 43 on each side thereof and in position to engage one or the other of the pins 42 when they extend through a short distance beyond either one or the other of the levers 31 or 32, so that when the pedal rod 35 is pushed down the lever 36 will engage one or the other of the ends of the pins and cause rotation of the bell crank levers 31 or 32 and one of the arms 38. The bell crank levers 90 29 being connected to one or the other of the bell crank levers 31 or 32, the bell crank lever 29 which is connected to the bell crank lever 31 or 32 will also be rotated about its pivot pin and cause one or the other of the frames 10 or 11 to be carried down so as to place one of the disks in the channel of 95 the track.

The rod 39 is connected to an arm 60 by a pin and slot for shifting the rod 39 to 100 shift the pins 42 in position of engagement with the semi-bosses or lips 43 to cause one or the other of the disks to enter a channel of the rail located beneath the disk. The arm 60 is connected to a sleeve 61 which 105 extends through the floor of the car to a position in front of the motorman. It extends to a bracket 62 above which is located an arm 63 which is pivotally connected to the sleeve 61. The bracket 62 is made in 110 the form of a sector and is provided with a notched flange 64. The arm 63 may be turned or slipped into the notches and thus may be slipped into the position to which it is turned. When the arm 63 is turned to the left the arm 60 will also be turned to the left, which will connect the bell crank lever 32 with the lever 36 so that when the foot pedal is pushed down a lip 43 of the bell crank lever 36 will cause the bell crank 115 lever 32 to be turned down, which will pull the bell crank lever 29 that is connected to the frame 10, that is, the frame of the left side of the car, through the bell crank lever 22 and cause the frame 10 to carry the disk 120 6 into the channel of the rail. When the arm 63 is turned to the right the rod 39 will shift the arms 38 so as to place the pin 42 which extends through the bell crank lever 31 into position of engagement with one of 125 65

the bosses 43, so that when the pedal is pushed down the bell crank lever 31 will cause the bell crank lever 29 which is connected to the frame 11 through a bell crank lever 22 to be operated. When the arm 63 is at an intermediate position neither of the pins 42 will be in position of engagement with the semi-bosses or lips 43.

- The normal positions of the rod 16 being 10 in a line from the centers of the channel members 12 and 13 and the ends of the fingers 21, the bell crank levers 22, though slightly rotated, will through the action of the spring 23 on the rod 16 operate to push 15 the frame 10 or 11 down and the spring 26 operating on the long arm of the bell crank lever to resist rotation of the bell crank lever, co-operates with the link 28 connected with one of the bell crank levers 29 to force 20 the frame and disk down so that the disk will be placed in the channel of the track. The rod 16 being placed in its normal position, that is, in line with the pivot pin 19 and the end of the finger 21, the disk will 25 be carried down in the plane of the flange of the wheel and immediately in front of the flange of the wheel. The disk is now in position to be turned angularly so as to engage the nose of the switch, which is done 30 by shifting the rod 16 to one or the other of the ends of the members 12 or 13 to which it may be connected by the ball 18.

- The rods 16 are connected together by a slender flexible rod 45, to which the rods 35 16 are pivotally connected. A cross bar 46 is located in parallel relation and beside the rod 45. The rod 46 is pivotally and loosely connected to the frames 10 and 11. Pulley wheels 47 are connected to the cross bar 46. 40 Cables 48 are connected to the cross bar 45 and pass over the pulleys 47. The cables 48 pass over pulleys 49 which are secured to a bracket 50. The bracket 50 is attached to the frame 1 of the car. The cables 48 45 also pass over the pulleys 51 which are attached to a weight 52. They also pass over pulleys 53 which are attached to the bracket 50. The cables are connected to the ends of a lever 54 which is connected by means 50 of a rod 55 to the lever 56. The lever arm 56 is pivotally connected to the rod 55 and is located above a bracket 65 which is also provided with a notched flange 66. The arm 56 may be placed in the notches of the 55 flange 66 to hold the arm 56 into the position that it may be placed and prevent rotation of the rod 55. When the arm 56 is rotated to the left the rods 45 will be shifted to the left to shift the rod 16 to the left and 60 so that under the action of the springs 23 one or the other of the disks will be turned. The disk is turned after the frame to which it is connected has been carried down so as to place the disk in the channel. In moving the frame down a short rotation of the

bell crank lever 22 compresses the spring 23 so that when the rod 16 is released from its position of alignment between the center of a member 12 or 13 the member to which the rod is connected will be rotated about the 70 pin 19 and cause the disk 6 to take its angular position relative to the track. The disk being rotatably supported in the pivoted arm 8 or 9, and being slipped along sideways, will engage the nose of the switch 75 and force it laterally. The disk 6 being sharply beveled on both sides, that is, the disks being provided with wedge-shaped edges, they tend to cling to the track and retain themselves in the channel of the 80 track as their beveled edges tend to prevent their being lifted out of the channel of the track. The disks thus operate to engage the noses of the switch which are located in the broadened portion of the channels of the 85 rails. As the car passes along the switches are thrown as may be desired by the motorman. When the arms 56 and 63 are turned to the left the car will turn off to the left on the branch track. When the arms 56 90 and 63 are turned to the right the car will turn off to the right on the branch track. When, however, the arm 56 is turned to the right and the arm 63 is turned to the left, the left disk will be placed in the channel 95 of the left rail and the switch will be thrown to the left to prevent the car from turning on the left branch and permitting it to move forward on the main line. When, however, the arm 56 is turned to the left 100 and the arm 63 is turned to the right the switch on the right side of the car will be so placed by the disk that the car will be prevented from turning to the right and will be permitted to move forward on the 105 main line.

When the car turns on a branch the trucks rotate short angular distances relative to the car frame or body. The relative movements are allowed for in the track 110 switch operating mechanism by the weight 52 having pulleys 51 over which the connecting cords or wires 48 pass, and the levers 22 which are yieldingly held in position by the springs 26 permit relative movements of the levers 29 without material movement of the frames 11 when the frames are up. When the truck passes onto the curves of the branches, however, the frames 11 may be lifted slightly, but the 120 disks have already performed the operation of throwing the track switch and may be at that time or later lifted to normal position by the motorman.

I claim:

1. In a car track switch operating mechanism, the combination of a pair of disks located substantially in the planes of the flanges of the wheels of the car, means for lowering either of the disks into the chan- 130

- nel of the track substantially in the planes of the flange of the wheel, and means operated by the lowering means for turning the disk to one or the other of two angular positions.
- 5 2. In a car track switch operating mechanism, the combination of a pair of disks located substantially in the planes of the flanges of the wheels of the car, means for lowering either of the disks into the channel of the track substantially in the planes of the flange of the wheel, means operated by the lowering means for turning the disk to one or the other of two angular positions,
- 10 15 and a manual means for controlling the disk turning means.

3. In a car track switch operating mechanism, the combination of pivoted disks supported on pivoted arms, pivoted channel members connected to the pivoted arms, rods having connector members, the connector members slidable in the channel

members for causing the channel members and the pivoted arms to rotate in one direction or the other, and means for moving 25 one or the other of the said rods.

4. In a car track switch operating mechanism, the combination of pivoted disks supported on pivoted arms, pivoted channel members connected to the pivoted arms, 30 rods having connector members, the connector members slidable in the channel members and the pivoted arms to rotate in one direction or the other, levers, springs operating 35 intermediate the levers and rods, pivoted frames for supporting the said arms, channel members and levers, and means operating on the levers for causing rotation of a frame, the channel member and arm supported thereby.

In testimony whereof, I have hereunto signed my name to this specification.

JOHN A. WEBER.
